UNITED STATES PATENT OFFICE.

EUGÈNE MULLARD, LAURENT VALENDUCQ, AND JEAN DUBOIS, OF PARIS, FRANCE.

READING LAMP.

Application filed June 17, 1920. Serial No. 389,753.

(GRANTED UNDER THE PROVISIONS OF THE ACT OF MARCH 3, 1921, 41 STAT. L., 1313.)

To all whom it may concern:

Be it known that we, EUGÈNE MULLARD, LAURENT VALENDUCQ, and JEAN DUBOIS, citizens of the Republic of France, residing all three at Paris, 64 Rue Amelot, in the Republic of France, have invented certain new and useful Improvements in Reading Lamps (for which we have filed an application in France on May 30, 1914, Patent No. 472,835), of which the following is a specification.

This invention relates to an electric lighting apparatus known as "reading lamp" which is chiefly designed for use in railroad wagons and ocean steamers.

In this apparatus, the lamp is constantly inclosed and is protected at least upon the major part of its periphery by a protecting casing, and is lighted and extinguished by the opening and closing movements of a portion of the said casing.

The accompanying drawings show by way of example two constructional forms of a lighting apparatus according to this invention.

Fig. 1 is a front elevation of one form of the apparatus or reading lamp, with the casing and the shutter removed.

Fig. 2 is a horizontal section of the same, with the shutter closed.

Fig. 3 is a cross-section along the line A—A of Fig. 1.

Fig. 4 is a rear elevation of the second form of the device.

Fig. 5 is side elevation of the same, in the open position.

Fig. 6 is a cross-section along the line B—B of Fig. 4, the device being in the closed position.

The apparatus represented in Figures 1 to 3 inclusive comprises a casing or frame 1 closed by a fixed cover 2 which contains an opening 3 in order to receive a swinging shutter 4. The lamp 5 is of cylindrical

shape and is provided with the circular contacts 6 at its ends; this lamp is pressed by means of two flat springs 7 and 7^a upon two insulating blocks 8 which are disposed upon the lower walls of the casing. The springs also serve to bring the current to the contacts 6, and they are mounted upon the insulating pieces 9 and 9^a, these latter being

fixed to the vertical bottom part of the casing by means of the screws 10. One of these springs is fixed to its respective piece 9 by a bolt whose nut 11 serves as a terminal for receiving one of the line wires. The other spring is held by the bolt 11^a which is electrically connected by a wire 11^b to a strap 13^a mounted on one end of the piece 9^a. The second line wire is received by a terminal 14 screwed upon a strap 13 similar to the strap 13^a and attached to the corresponding end of the piece 9. Each of the members 13 and 13^a supports by means of lugs a vertical shaft or pin 15, upon which a contact piece 16 or 16^a is adapted to swing, this piece being submitted to the action of the spring 17.

The protecting shutter 4 provided with the two lugs 18 is adapted to swing about the shafts or pins 19 mounted on the walls of the casing 1. One of these lugs 18 carries flattened portions adapted to receive the pressure of the lever which is articulated upon one side of the casing and is submitted to the action of the spring 21, these flattened parts being so disposed that the shutter shall be held in its two extreme positions by the pressure of the levers 20, or in the open or closed position, as indicated by the dotted line in Fig. 3.

The shutter 4 carries attached thereto an insulating piece 27 upon which is mounted the insulated contact piece 22 designed to make connection between the pieces 16 and 16^a, in the open position of the shutter. The swing of each of these latter pieces is limited in either direction by means of suitable stop pieces.

With the lamp mounted in position under the springs 7 and 7^a, the opening of the shutter has the effect of engaging the member 22 between the pieces 16 and 16^a, and in consequence the current will now pass by way of 11, 7, 5, 7^a, 11^a, 13^a, 16^a, 22, 16, 13 and 14. The lamp will thus be lighted at the same time that it is uncovered by the shutter.

Inversely, when the shutter is closed, the member 22 comes out from between the pieces 16 and 16^a, and the lamp is thereupon extinguished as well as closed up. The member 22 carries with it in its backward movement the pieces 16 and 16^a up to a cer-

tain point, and then releases them when the latter are arrested by their stop pieces; whereupon the springs 17 will snap back the pieces 16 and 16^a, thus avoiding the injurious effect of sparking at the contact, so that currents of any voltage can be used.

The reading lamp represented in Figures 4 to 6 differs essentially from the foregoing in the fact that the lamp is now contained 10 in a swinging protecting casing 4^a which acts at the same time as a reflector and also serves as a shutter to close the opening in the frame 1^a, instead of having the lamp mounted in fixed position in the casing 1; 15 the lamp is constantly protected, at least upon the greater part of its periphery, and is lighted and extinguished by the movement of one of the protecting members, in the present case by the swinging movement 20 of the casing 4^a.

The casing 4^a consists of an open box-shaped member mounted by means of the journals 19^a upon the lugs of a fixed frame 1^a. The two spring clamps 7^b and 7^c are 25 attached to the bottom of the said casing in such manner as to be insulated therefrom, by means of the insulating blocks 8^a. These clamps are so disposed that the axis of the lamp held therein shall coincide approximately with the axis of the journals 19^a.

The line wires are received by two terminals 14^b and 14^c which are attached by means of the insulating pieces 23 to the lugs of the frame 1^a; each of the said terminals is provided with a fixed arm 13^b or 13^c having swinging thereon a contact member 16^b or 16^c which is acted upon by the spring 17^a. When the casing is inclined (Fig. 5), the members 16^b or 16^c are caused 40 to bear upon the contact members 11^b and 11^c, which are attached to the bottom of the casing in such manner as to be insulated therefrom, and which are connected to the spring clamps 7^b and 7^c through their attachment bolts.

Upon inclining the casing 4^a as shown in Fig. 5, the members 11^b and 11^c will make contact with the members 16^b and 16^c, whereupon the current will pass by way of 50 14^b, 11^b, 16^b, 7^b, 5, 7^c, 16^c, 11^c and 14^c, and the lamp will now be lighted. When the casing is brought into the upright position, the members 11^b and 11^c will be separated from the members 16^b and 16^c, and the lamp 55 will be extinguished and closed up at the same time. In this movement the first mentioned members will draw along the swinging members 16^b and 16^c in the first place, and will then release them and snap back 60 under the effect of the springs, thus avoiding all sparking at the contacts.

The casing 4^a is held in its two end positions through the pressure of a lever 20^a which is articulated upon a lug on the frame 65 1^a and is acted upon by the springs 21^a, the

end of the lever being provided with a roller and working upon a cam-shaped projection 24 integral with the casing 4^a. In order to prevent any sudden shocks to the casing when at the end of its movement, the rubber buffers 25 and 26 are disposed on either side of the casing and also upon the frame 1^a.

Claims:

1. In an electric apparatus termed reading lamp, the combination of a frame adapted to be secured to a partition and provided with an opening, an electric lamp bulb supported by said frame in the rear of said aperture, the axis of said bulb being horizontal, a shutter serving to close said aperture, the said shutter pivoting upon an axis adjacent the axis of said bulb, and a quick-break device for electric current comprising a contact with rocking elements secured to said frame, springs for effecting the rapid rocking movement of said elements during the closing of said aperture, a contact member disposed upon said shutter and adapted to engage said rocking elements, and means for electrical connection between said lamp bulb and said contact members.

2. In an electric lighting apparatus known as reading lamp, the combination of a stationary supporting member, a swinging casing pivoted upon the said supporting member, spring clamps fixed within the said casing, an incandescent lamp having upon the ends thereof electric contact rings 95 adapted for insertion into the said clamps, the pivot shaft of the said casing and the axis of the lamp being located in proximity to each other, and contact means disposed upon the supporting member and upon the casing, the said means being adapted for opening and closing the circuit of the lamp according to the direction in which the said casing shall be rotated.

3. In an electric lighting apparatus known as reading lamp, the combination of a fixed support, a swinging casing pivoted upon the said support, an incandescent lamp fixed within the said casing, a projection upon the said casing, a spring-actuated lever articulated upon the said support, and a roller pivoted on the said lever and adapted to engage to said projection of the casing for the purpose set forth.

4. In an electric lighting apparatus known as reading lamp, the combination of a fixed support, a swinging casing pivoted upon the said support, two spring clamps fixed within the said casing, an incandescent lamp whose ends are inserted into the said clamps, insulating blocks disposed upon the said supporting member, electric terminal pieces mounted upon the said blocks, forked contact members pivoted upon the said terminal pieces, springs for maintaining the

said contact pieces in the inoperative position, and contact members disposed upon the said swinging casing, these latter members being connected to the said clamps and adapted for insertion into the said forked contact members when the swinging casing is rotated in a certain direction.

In testimony that we claim the foregoing

as our invention, we have signed our names in presence of a subscribing witness.
